IMPROVEMENT IN STEAM GENERATORS.

HERRMAN S. SARONI, OF BALTIMORE, MARYLAND.

Letters Patent No. 60,562, dated December 18, 1866.

The Schedule referred to in these Letters Patent and making part of the same.

TO ALL WHOM IT MAY CONCERN:

Be it known that I, HERRMAN S. SARONI, of the city and county of Baltimore, and State of Maryland, have invented certain new and useful improvements in Apparatus for Generating Steam; of which the following is a full, clear, and exact description, reference being had to the annexed drawings, making a part of this specification, in which—

Figure 1 represents a central vertical section through my apparatus.

Figure 2 represents a central vertical section through the water-drum.

Figure 3 represents a top view of the water-drum; and

Figure 4 represents a top view of a series of drums, arranged for use with boilers of large capacity.

It is the object of my invention to generate steam rapidly with a burner or burners adapted to the use of mineral oils or other liquid hydro-carbons as fuel; to which end my improvement consists—

First, in a shallow water-drum or heater, interposed between the burner and the boiler; second, in so combining the boiler and the tubular heater or water-drum as that a space shall be left between the two to form a combustion chamber; third, in placing tubes within the water-drum or heater, to augment the heating surface exposed to the direct action of the flame generated by the burner.

In illustrating my invention by this example, I have shown it applied to a vertical cylindrical tubular boiler, but it is obviously applicable, also, to flue or tubular boilers of any shape adapted to a horizontal position. The boiler A is cylindrical, and contains a number of vertical tubes, *a a*; it is provided with a spirally-coiled steam pipe, B, communicating with the steam chamber, and furnished with a safety-valve, *b*. The boiler has steam and water-gauge cocks, 1, 2, and 3, suitably placed to keep the water at a proper level. The shell of the boiler terminates in a flared flange, C, to enable it to be so connected with a tubular heater, D, as to leave a clear space between the bottom of the boiler and the top of the tubular heater D, on which it rests, the heater D being itself supported on a cylindrical furnace-chamber, E, for the burners, or on a properly constructed furnace wall. Pipes *d* and *d'* connect the boiler A with the tubular heater, and the pipe *d* is connected with the pump by a pipe, *e*, through which the required supply of water is obtained; and the flow of water from the pump to the heater, and between the heater and the boiler, is under the control of a globe-valve or three-way cock, F. The tubular heater D is a shallow drum, of the diameter of the bottom of the boiler, having short tubes, *f*, passing vertically through it, to permit the flame from the burners to enter and pass into the space between the heater D and the boiler A, this space constituting a combustion-chamber, from which the heat passes off through the open tubes in the boiler to a suitably placed chimney. The burners *g* rise from a proper supply-pipe, G, fed from any properly placed reservoir, and the conductors attached to the burner may touch the heater-drum, or be placed so near to it as to conduct the desired amount of heat to vaporize the oil in the supply-pipe G. Instead of the drum described, I use, for convenience in different situations, a water-drum H, which consists of a circular shallow drum, with tubular openings *h*, and an entrance opening *i*, and exit opening *k*, the tubular openings permitting the passage of the flame from the burners, and the openings *i* and *k* permit the flow of a current of water through the drum. To adapt my tubular heater to boilers of large surface, I arrange water-drums H', fig. 4, in any numbers and size required for the determined number of burners to be used, in rows between pipes L and L', connecting these water-pipes with the drums and with each other by connecting pipes *l*, the water from the pump entering the pipe L at *m* and *m'*, and passing into the boiler after being heated from the pipe L', at *n* and *n'*.

I have only described a cylindrical heater-drum, but of course the form is indifferent, and my invention will be perfectly effective, whatever the shape of the drums. The operation is as follows: The boiler being filled to the proper height, the steam pipe being connected to the engine, the water pipe to the pump, and the oil pipe to the reservoir, a fire is placed beneath the burners, and held there until vaporization takes place, and the vapor passing from the burners is ignited, and when the oil pipe becomes sufficiently heated, the vaporization continues, and the starting fire is withdrawn from beneath the burners; the flame from the burners passes over the under surface of the heating drums, and ascends through the tubes in the drums to the combustion chamber between the drums and the bottom of the boiler, where the flame, mingling with a larger body of atmospheric air, combines with its oxygen and causes nearly all the heat there generated to pass through

the boiler tubes and be absorbed by the water in the boiler, the surplus passing around the steam pipe, and serving to superheat the steam therein, to the chimney, while the water becomes highly heated in the heater and circulates freely through it and the boiler, when the steam is rapidly generated, and with a marked economy in fuel and attendance. Thus it will be seen that the feed water is heated in the drum before entering the boiler through the pipe *d'*, and that when the feed water is shut off, a circulation through the drum and boiler will be established by the arrangement of the pipes *d* and *d'*.

What I claim as my invention, and desire to secure by Letters Patent, is—

1. A shallow water-drum or drums, or tubular heater or heaters, interposed between the burner or burners and the boiler, substantially as and for the purpose described.
2. The combination of the boiler with the tubular heater, substantially as described, and so arranged that a space shall be left between them, for the purpose set forth.
3. The combination of the boiler, tubular drum, and burners, substantially as described, so that the drum shall act as a heater cap to the burners, and permit the flame to pass to the bottom of the boiler, as set forth.

In testimony whereof I have hereunto subscribed my name.

HERRMAN S. SARONI
